UNITED STATES PATENT OFFICE

WILLIAM W. NICODEMUS, OF TAYLORVILLE, ILLINOIS

BRACKET FOR SUPPORTS

Application filed October 2, 1928. Serial No. 309,842.

This invention relates to brackets for supports and more particularly to a bracket capable of being arranged in multiple to enable its convenient use in mounting garment hangers, gambrels or other supports.

An important object of the invention is to provide a device of this character which is so constructed that any portion of the series may be removed to permit access to a selected support arranged in the series without disturbing the relative positions of the supports of the removed portion of the series and without disturbing the remainder of the series.

15 A further object of the invention is to produce a device of this character which is so constructed that it may be very readily combined with supports of widely varying character and which will maintain the supports in such spaced relation that there will not be undue contact of articles supported thereby.

20 A still further object of the invention is to provide in a construction of this character an arrangement such that when desired, the brackets may be mounted upon other supports than a second bracket of the series, thus enabling the same to be arranged upon a stretched line or wire or other suitable support.

25 These and other objects I attain by the construction shown in the accompanying drawings, wherein for the purpose of illustration is shown a preferred embodiment of my invention and wherein:—

30 Figure 1 is a side elevation showing a series of brackets constructed in accordance with my invention;

35 Figure 2 is a plan view, one of the brackets being shown partially in section;

Figure 3 is a vertical sectional view through the bracket and a portion of an attached bracket;

40 Figure 4 is a front elevation of the bracket;

Figure 5 is a fragmentary side elevation of the supporting arm showing a slight modification of the structure thereof.

45 Referring now more particularly to the drawings, the bracket comprises angularly

and preferably perpendicularly related arms 10 and 11, of which the arm 10 will herein-after be referred to as the vertically disposed arm and the arm 11 as the horizontally disposed arm. As will hereinafter 55 become obvious, these terms are arbitrarily employed to designate the general direction of extension of the arms and not any actual fixed relation thereof. The vertical arm 10 is made relatively broad and flat and at its 60 upper end has outwardly extending ears 12 adapted to engage against fingers of the hand which engage the arm 12 at the sides thereof and to provide a limit, preventing downward sliding movement of this arm 65 through the fingers. The arm, adjacent its upper end, has formed therein a rectangular opening 13, the purpose of which will presently appear.

Beneath this opening, an upwardly and 70 inwardly inclining slot 14, which opens at its lower end though one side of the arm, provides communication with a centrally disposed cove 15. The slot permits admission to the cove of a stretched rope, wire 75 or similar support from which the arm may be suspended, if desired.

The horizontal arm 11 is made of a desired length and is likewise flat and relatively broad, having its greatest dimension 80 vertically directed. The outer end of this arm, which may be of any desired length, dependent upon the spacing which is desired between the mounted supports S, is provided with a nose 16, which is of approximately 85 the same width and depth of the opening 13 of the vertical arm. The outer end of this nose is slightly reduced both transversely and longitudinally, as will be more obvious by a comparison of Figures 1 and 2 to permit the ready engagement of the vertical arm of a second support therewith by passing the nose through the opening 13. In its upper surface, the nose is formed with a 90 notch 17, the outer wall 18 of which or that wall most remote from the vertical arm 10 is spaced from the front face of a shoulder 95 20 on the arm 11 a distance closely approximating the thickness of the arm 10. The lower face 19 of the nose is spaced from 100

the lower edge of the arm to provide the shoulder 20 on the arm 11, which contacts the inner face of the arm 10 of an applied bracket beneath the lower edge of the opening 13 thereof. To assist in maintaining an applied bracket in rigid position, the outer end of the arm 11 is preferably widened, as at 21, to increase the width of the shoulder 20, the shoulder being arranged in alignment with the inner face or wall 22 of the notch 17. The arm 11 may likewise be so constructed that the nose is disposed below the upper edge thereof, with the result that the arm 11 above the nose will engage with the outer face of the arm 10 above the opening 13, as illustrated at 23 in the modified form of Figure 5.

It will be obvious that in the use of the device, one of the brackets must be first applied to the wall or other support by which the bracket series is to be carried. Subsequent brackets can be secured to succeeding brackets by simply engaging such brackets with the succeeding bracket by passing the opening 13 over the nose and seating the upper wall of the opening 13 upon the bottom wall of the notch 17 of the nose, the arm 10 being held against movement in opposite directions by the walls of the notch and the shoulder 20. The applied bracket will be securely held in position. While the construction illustrated is such that the brackets will be disposed in descending series, it will, of course, be obvious that by varying the inclination of the arms 10 and 11 to one another, the steps of such descending series may be either varied, as desired, or completely obliterated. It will also be obvious that the supports S must be spaced from one another variable distances to enable various types of supports to be employed. In the present illustration, the supports S comprise garment hangers integrally secured to the arms 11 and in a construction of this character, a minimum space between adjacent supports S may be provided. In the use of brackets of this character, however, the spacing of the supports would have to be varied to insure the proper spacing for the supported meats or fowls.

When it is desired to remove a particular bracket of the series to secure the element mounted upon the support S thereof, this may be readily accomplished by engaging the next succeeding bracket, disengaging it from the desired bracket together with all succeeding brackets of the series. The desired bracket is then removed and the remainder of the series replaced by engagement with the bracket which had originally supported the desired bracket.

It will be obvious that a construction of this character lends itself to many usages which are not herein illustrated or suggested and it will also be obvious that this construc-

tion is capable of a considerable modification without departing from the spirit of the invention. I accordingly do not limit myself thereto except as hereinafter claimed.

I claim:—

1. A bracket for supports comprising angularly related arms, one arm of the bracket having an opening and the outer end of the other arm of the bracket being provided with a shoulder and a nose extending beyond the shoulder for engagement in the opening of a similar bracket, said nose having in its upper face a notch the outer wall of which is spaced from the shoulder a distance equal to the thickness of the first named arm, the shoulder being of greater breadth than the opening. 70 75 80

2. A bracket for supports comprising angularly related arms, one arm of the bracket having an opening and the outer end of the other arm of the bracket being provided with a shoulder and a nose extending beyond the shoulder for engagement in the opening of a similar bracket, said nose having in its upper face a notch the walls of which are spaced apart a distance equal to the thickness of the first named arm and the inner wall of which coincides with the shoulder. 85 90 95

3. A bracket for supports comprising a vertical arm having an opening, and a horizontal arm having a shoulder and a nose extending beyond the shoulder and provided in its upper side with a notch having one of its side walls alined with the shoulder. 95

In testimony whereof I hereunto affix my signature. 100

WILLIAM W. NICODEMUS.
